METHOD OF AND MEANS FOR FLOWING
OIL WELLS

George M. Wells, Upper Montclair, N. J.

Application March 2, 1937, Serial No. 128,561

7 Claims. (Cl. 166—21)

My invention relates to a method of and means for flowing oil wells.

An object of my invention is to flow petroleum from wells which could not be flowed by methods available heretofore, and to increase the rate of flow as well as the length of time over which a well will flow after it has been brought in, thereby increasing the total amount of petroleum recoverable from a well.

More particularly, my invention has as an object to obtain petroleum free from sand, by employing filtering means that prevents the petroleum bearing formations from being removed along with the petroleum, and which means also does not clog with sand so as to stop the flow.

An additional object of my invention is to provide a method utilizable in connection with wells that are drilled with a heavy circulating drilling fluid that is retained in the well in a circulating condition when the well is not being flowed.

In drilling an oil well and preparing the same for flowing petroleum therefrom, the common practice is to drill down through the various formations until one or more strata are reached that contain petroleum that it is desired to remove. These strata containing the petroleum are generally composed of sand, shales or other porous material containing small voids. The petroleum generally occurs as a fluid saturating or at least partially filling the voids in the porous material. The petroleum in such strata is generally under a great pressure. As the petroleum is removed through the well it flows under pressure through the porous formation towards the well.

At all times during a drilling operation and subsequently except when the well is being flowed, it is necessary to have the well filled with a heavy viscous mud, termed drilling fluid, which is circulated by pumps. It is this circulating drilling fluid that removes the strata cuttings that are cut away by the drilling tool or any other strata material that may be in the well due to sluffing or cavings. At all times, while the drilling fluid is in the well, it is essential that the fluid should be kept in circulation in order to prevent any strata particles in the fluid from settling out. If a given critical velocity were not maintained, any strata particles in the fluid would be deposited at the bottom of the well and would have to be drilled out again.

When a petroleum bearing stratum is reached in the drilling, the weight of the column of the drilling fluid in the well exerts a force which

acts in opposition to the pressure on the petroleum in the porous stratum, and as long as the drilling fluid is present, the petroleum is prevented from flowing through the stratum into the well.

In accordance with the common practice of flowing a well, the drilling apparatus is withdrawn after a petroleum bearing stratum is reached; the casing is then cemented, the well under-reamed and a pipe is inserted at the end of which is a screen having very small openings which are intended to filter sand from the petroleum. The circulating drilling fluid is then gradually replaced by water and the pressure exerted against the petroleum in the porous stratum will be progressively lessened because of the lower specific gravity of the water. This reduced pressure is generally such as to permit the petroleum to flow into the well through the porous formation.

The sand of the porous stratum disintegrates or moves under the flow of the petroleum. Before the flow is started, the pressure exerted by the drilling fluid holds the porous sand formation in its original position. However, when this pressure is lowered by replacing the drilling fluid with water, and during the time the petroleum is flowing through the stratum, there is nothing to hold these formations in position. There is often an initial caving of the sand against the screen, or a bodily movement of a large mass of sand mixed with the mud that has penetrated into the formation, which moves against the screen. Particularly is this the case when the petroleum is under great pressure and when the initial velocity of the petroleum is relatively high. When petroleum flows through the stratum to the well, it also carries sand with it, and if the screen has not become clogged by an initial caving, it is often clogged by the sand flowing with the petroleum. As a result, the flow of petroleum through the screen and into the pipe is considerably reduced or stopped entirely. Numerous instances are of record in which a well does not flow at all, or flows freely at first followed by a quick decrease until the flow is small or nil.

If the openings in the screen are made sufficiently small so as to filter out most of the sand, the small openings are easily clogged with sand particles and mud. During the drilling operation a certain amount of the drilling fluid penetrates the porous formation, and the mud particles of the drilling fluid, which are in the formation, are not removed by the washing operation. As the petroleum moves into the well through the stratum, it brings with it these fine

mud particles that are mixed with the sand. The screen becomes completely clogged or cemented over with this mixture of mud and the small sand particles. The flow of petroleum is stopped immediately.

If the screen openings are made larger, the small sand and mud particles will flow through the openings in the screen and only the sand particles which are larger than the screen openings will be filtered. As the small sand particles flow through the openings they cut the screen, due to their high velocity and abrasive action. Before a filtering action can be established by the larger particles the screen openings generally will have been cut to such a large size that not even the larger sand particles are restrained and there is no filtering action whatsoever.

In screens having larger openings the petroleum flows at a greater velocity and carries a larger amount of sand particles through the openings, both of which augment the cutting action.

It might be supposed that an effective filtering network of sand particles could be built up around the screen by employing a screen having large openings which permits the mud and small particles to pass through the screen initially and exclude only the larger sand particles. In such instances, however, by the time such a condition has been established, the quantity of sand which has passed through the screen is usually so great that the screen is cut so that the openings are not able to even hold back the larger sand particles.

The employment of a screen as a filtering medium, therefore, gives rise to a dilemma in which the use of openings of any size have such disadvantages as to render a screen a very undesirable filtering means as compared with that available in accordance with my invention.

In the usual prior practice, after a screen has become clogged, an attempt is first made to remove the screen by pulling it out and inserting a new screen. The sand in the formation, however, usually has become packed against the screen so tightly that the screen sticks and cannot be removed. If the well is to be flowed further or drilled deeper, it is necessary to cut out the screen and remove it in pieces. This usually proves to be a tedious and expensive operation.

I have heretofore proposed a method of flowing an oil well by placing iron or steel balls, or equivalent material, in the well to hold the porous formation in position and prevent it from caving. The balls also act as an effective filtering medium for excluding the sand from the petroleum. By that method, the well can be flowed at high rates over a long period of time, and petroleum obtained free from sand.

That method is particularly suitable when the petroleum bearing stratum is of relatively small depth. When the stratum is relatively deep the iron or steel balls tend to move down through the sand stratum until they are supported by a firm material. In employing that method for flowing petroleum from a relatively deep sand stratum, a larger quantity of balls is necessary.

I have now discovered that all of the unobvious advantages of my previously proposed method may be availed of, and that the disadvantages thereof may be eliminated if the balls are confined by a perforated restraining means. By such a means the balls are held immovable in a fixed position within the well and cannot move in the sand formation. The method is suitable in

flowing oil from a sand stratum of any depth and particularly from a relatively deep stratum.

The exact procedure to be followed in practicing my invention will depend somewhat on the type of formation and the condition of the well at the time the flow is initiated. My invention will be more fully understood from the following typical illustrative examples that will be described in connection with the drawing forming a part of this specification and in which Figures 1 and 2 are views partly in section and partly in elevation of wells being flowed by my process.

In accordance with the illustrative embodiment of my invention shown in Figure 1, the well is drilled to a petroleum bearing stratum which it is desired to flow and the casing is cemented in accordance with the procedure well understood in the art. A pipe, closed at the bottom and having the lower end perforated, is partially filled with a sufficient quantity of iron or steel balls to fill the portion of the pipe adjacent the perforations in the lower end and usually extend somewhat above the perforations. The pipe is then lowered into the well so that the perforated portion extends into the petroleum bearing stratum. The drilling fluid is then gradually replaced by water and because of the decreased pressure on the petroleum in the stratum, due to the lower specific gravity of water, the petroleum begins to flow in from the stratum, through the perforations, through the voids in the balls, and up through the pipe.

It is also possible to insert the perforated pipe into the well without the balls, and to pour the balls into the pipe after it has been placed in the well.

The petroleum initially flowing from the formation when the well is brought in usually carries sand and mud with it. The particles of sand vary in size, and the larger particles become entrapped in the voids in the balls. As the voids become filled with the larger sand particles, these particles in turn hold back smaller sand particles. This continues until a perfect filtering network of sand particles is formed in the voids of the balls, which holds back sand particles of all sizes. After the well has been flowing for a short time, this filtering network is established and is effective in holding back even the finest sand particles, and as a result the well flows clear of sand.

During the initial flow after the well is brought in, while a filter of sand particles is being established in the voids of the balls, the fine sand and the mud is not held back and reaches the surface of the well. The mixture of mud and other fine particles, which would normally clog and seal the small openings in a screen, will have initially passed through the voids in the balls. All of the mud in the formation will have flowed out of the well by the time the final filtering network that excludes smaller sand particles is established. The initial flow of petroleum contains sand, but this is inconsequential as compared with the flow that is subsequently obtained from sand.

In view of my explanation, it will be understood that materials of a relatively low specific gravity, such as gravel or crushed rocks, could not be successfully employed as a filtering medium; such materials are not heavy enough to be held in position in a perforated restraining means. Filtering materials having a specific gravity of the same order as the specific gravity of the sand particles would be moved, or even raised to the surface, by the flowing petroleum, because velocities of the petroleum which are

sufficient to flow the sand particles through a strata are sufficient to flow material of similar specific gravity being employed as a filtering medium. By employing iron or steel balls as a filtering medium, I am enabled to flow the well free from sand, at an increased rate, and over a long period of time.

Because of the large number of balls and the many voids therein through which the flow of the petroleum is distributed, the petroleum flows through the voids at a relatively low velocity, and any cutting action of the sand that originally flows through the balls is minimized. Further, due to the hardness of the balls, they are not cut as readily as a screen. The flow of the sand is also arrested sufficiently before any cutting takes place that would interfere with the action I have described.

Other advantages are also obtained by using iron or steel balls. During the time the filter network of sand particles is being established in the voids of the balls, and subsequently during the continued filtering action, it is essential that the filter structure be preserved. Any movement of the balls would disturb the filter and release the sand in the voids of the balls. This, of course, is undesirable because the petroleum would not only contain this released sand, but also because the filter network would be destroyed and would have to be re-established. Because of the high specific gravity of the balls their weight holds them firmly and securely in the perforated restraining means and they resist movement that would be imparted to material of less specific gravity by an unevenness in the pressure of the flow.

In accordance with the illustrative example shown in Figure 2 the oil well is provided with a casing that extends through a petroleum bearing stratum. At a suitable point in the casing, generally near the bottom but at any point in the petroleum bearing stratum, the casing is sealed by cementing a plug therein according to procedures well known in the art. The casing is then perforated above the plug and adjacent the petroleum bearing stratum. During the perforating and at all times prior thereto, the drilling fluid is circulating and the weight of the fluid prevents the petroleum from entering through the perforations in the casing. Iron or steel balls are then poured into the casing; they descend through the circulating fluid and rest upon the cement plug, extending upwardly in the casing adjacent the perforations and into the imperforate portion of the casing if desired. Water is then substituted for the drilling fluid and the pressure decreased in the usual manner; the petroleum will then begin to flow in from the stratum. It enters the perforations in the casing and then flows between the voids in the balls passing upwardly out through the casing or through a center pipe that is often employed for that purpose. The sand which initially flows through the stratum with the petroleum and enters the perforations in the casing will become lodged in the voids between the balls and a filtering network will be built up in the balls which will effectively eliminate the flow of further sand as has been described in detail heretofore.

I have pointed out heretofore that the drilling fluid is always circulating at a velocity sufficient to keep any strata material in suspension. The balls, being of a much higher specific gravity than the strata material, will move downwardly under gravity against the upward flow of the

drilling fluid as soon as the balls are inserted into the casing, and they will settle in position in the perforated restraining means. Filtering material having a lower specific gravity, for example, gravel and crushed rock, could not be inserted in the well in this manner against the flow of the drilling fluid because the velocities of the drilling fluid which would keep strata material in circulation would also circulate such filtering material. A particular reason for keeping the fluid circulating at a velocity that will keep strata material in suspension, is to prevent it from settling in the voids of the balls before the well is washed and brought in. If the strata material settles in the voids, it is very difficult to remove by washing.

Although the balls are heavy enough to be inserted against the velocity normally maintained in the circulating drilling fluid, nevertheless the balls are not so heavy as to prevent their subsequent removal by a temporary higher velocity of the fluid specially introduced for that purpose.

In many instances a casing extends through a number of petroleum bearing strata. In accordance with my invention, a plug is cemented at each stratum it is desired to flow. The casing is then perforated adjacent the stratum and iron or steel balls are introduced as described above.

In accordance with my invention, it is possible to re-establish the flow in oil wells having clogged screens by perforating the screen and then introducing iron or steel balls to fill the screen and the tube inside thereof.

It is particularly desirable that as the well is brought in, the flow should be established in such a manner that it will continue uniformly over a long period of time, and not necessitate repeated adjustments or changes in the equipment used in flowing the wells. I found that the iron and steel balls employed in accordance with my invention accomplish this purpose admirably with much more uniformity and dependability of results than has been obtained heretofore.

By means of my invention it is possible to flow petroleum from a strata containing such fine sand that it has heretofore not been regarded as feasible to remove the petroleum therefrom by methods heretofore available. The filtering network provided by the balls and the sand entrapped therein, operates so effectively that an extremely fine sand stratum may be flowed, and petroleum obtained from a stratum which has heretofore been regarded as unflowable.

The size of the balls may vary over wide limits depending upon the size of the well, the rate at which it is to be flowed, the character of the formation, and the size of the sand. When the sand particles are extremely fine I have obtained excellent results by the use of BB shot. If the sand formation contains particles of relatively larger size, larger balls may be used; for example, from $\frac{1}{4}$ inch to $1\frac{1}{2}$ inches diameter. The size of the perforations in the restraining means must be adjusted so as to be smaller than the size of the balls.

Heavy material other than iron or steel balls, having the capability of forming suitable voids may be used in my invention as an equivalent of balls, provided such material has the necessary high specific gravity in order that it may function in the manner pointed out heretofore. Such heavy material has a specific gravity of twice, or even two and one-half times, the specific gravity of the formation. Such material

will preferably have a specific gravity of six, or even seven to eight. Other metals, such as lead, or alloys having the prerequisite specific gravity may be used. Other heavy materials such as ores of the requisite specific gravity and hardness may be employed.

The shape of the material may also vary. Material having a uniformity coefficient of substantial unity is preferred. The volume of the 10 voids in such material will be a maximum and the voids will be uniformly distributed. This permits the largest quantity of petroleum to flow through the voids and due to the uniformity and even distribution of the voids the filter network 15 of sand particles will be formed more readily. The surface need not necessarily be spherical and by the expression "void-forming subdivided material" used hereinafter, I refer to any material, which when brought together, will leave suitable voids between the individual pieces of the 20 material. A subdivided material having a uniformity coefficient of unity represents the ideal.

It will be appreciated that many other modifications may be made in the exact procedure of flowing a well in accordance with my invention, depending upon the type of formation and the condition of the well at the time the flow is started. All such procedures in which void-forming material of a high specific gravity is introduced in a 30 well and retained in position therein are intended to be within the scope of my invention, as set forth in the following claims.

I claim:

1. In an oil well, an apparatus for flowing petroleum from the well and for maintaining the flow against stoppage comprising a rigid perforated restraining means in said oil well adjacent the petroleum bearing stratum thereof, and a void forming sub-divided material held in 35 said restraining means and adjacent said perforations, said void forming material having a specific gravity of at least twice the specific gravity of the petroleum bearing stratum, whereby said void forming material is held by the action of 40 gravity in said perforated restraining means and is undisturbed in its filtering action by petroleum flowing through said void-forming material at a 45 velocity that normally causes sand to flow with petroleum.
2. In an oil well, an apparatus for flowing petroleum from the well and for maintaining the flow against stoppage comprising a rigid perforated restraining means in said oil well adjacent the petroleum bearing stratum thereof, and iron 50 balls held in said restraining means adjacent said perforations whereby said iron balls are held by the action of gravity in said perforated restraining means and are undisturbed in their filtering action by petroleum flowing through the voids 55

in said iron balls at a velocity that normally causes sand to flow with petroleum.

3. In a method of flowing an oil well drilled to a petroleum bearing stratum and containing a circulating drilling fluid, the steps comprising 5 inserting into said well within a rigid perforated restraining means, a void-forming sub-divided material having a specific gravity of at least twice the specific gravity of the petroleum bearing stratum, and then washing said well to remove the drilling fluid, whereby said material is restrained against movement in the well and filters the petroleum flowing therethrough.

4. In a method of flowing an oil well drilled to a petroleum bearing stratum and containing 15 a circulating drilling fluid, the steps comprising inserting iron balls into said well within a rigid perforated restraining means, and then washing said well to remove the drilling fluid, whereby said iron balls are restrained against movement 20 in the well and filter the petroleum flowing therethrough.

5. In a method of flowing an oil well drilled to a petroleum bearing stratum and containing a circulating drilling fluid, the steps comprising 25 inserting into said well a perforated restraining means and a void-forming sub-divided material having a specific gravity of at least twice the specific gravity of the petroleum bearing stratum, which material is held in said restraining 30 means, and then washing said well to remove the drilling fluid, whereby said material is restrained against movement in the well and filters the petroleum flowing therethrough.

6. The method of flowing an oil well which 35 contains a rigid circumferential restraining means and in which a drilling fluid is circulating, the steps comprising sealing said restraining means adjacent a petroleum bearing stratum, perforating said restraining means, introducing 40 thereinto a void-forming sub-divided material having a specific gravity of at least twice the specific gravity of the petroleum bearing stratum, and then washing said well to remove the drilling fluid, whereby said material is restrained against movement in the well and filters the petroleum flowing therethrough. 45

7. The method of flowing an oil well which contains a rigid circumferential restraining means and in which a drilling fluid is circulating, 50 the steps comprising sealing said restraining means adjacent a petroleum bearing stratum, perforating said restraining means, introducing iron balls thereinto, and then washing said well to remove the drilling fluid, whereby said iron 55 balls are restrained against movement in the well and filter the petroleum flowing therethrough.

GEORGE M. WELLS.
